UNITED STATES PATENT OFFICE.

HUBBARD PARKER, OF CHICAGO, ILLINOIS; JENNIE C. PARKER EXECUTRIX OF SAID
HUBBARD PARKER, DECEASED.

JOURNAL-BOX BEARING.

Application filed November 7, 1921. Serial No. 513,458.

To all whom it may concern:

Be it known that I, HUBBARD PARKER, a citizen of the United States, and a resident of Chicago, in the county of Cook and State 5 of Illinois, have invented a new and useful Improvement in Journal-Box Bearings, of which the following is a full, clear, and exact description.

My invention relates to improvements in 10 journal box bearing, and it consists in the combinations, constructions, and arrangements herein described and claimed.

An object of my invention is to provide 15 a journal box bearing which is of the roller type, and which can be readily applied to a standard railway car journal box without altering the construction of the journal or box.

A further object of my invention is to 20 provide a device of the type described which can be readily applied to a standard railway car journal box in the same manner as the present journal bearing is applied, i. e., without the necessity of disassembling the 25 box from the journal.

A further object of my invention is to 30 provide a device of the type described which permits the required longitudinal play of five-eighths of an inch between the journal and the box.

A further object of my invention is to 35 provide a device of the character described which has a novel means for oiling the bearing.

A further object of my invention is to 40 provide a device of the type described in which the roller bearing is of novel construction and is of the flexible type.

A further object of my invention is to 45 provide a device of the type described in which the bearing sleeve is of novel construction.

Other objects and advantages will appear 50 in the following specification, and the novel features of the invention will be particularly pointed out in the appended claims.

My invention is illustrated in the accompanying drawings, forming part of this 55 application, in which—

Figure 1 is a longitudinal section of the device as applied to a standard journal box,

Figure 2 is a section along the line 2—2 of Figure 1,

Figure 3 is a section along the line 3—3 of Figure 1,

Figure 4 is a plan view of a portion of the roller chain used in the device,

Figure 5 is a view of the disassembled parts used in the roller chain,

Figure 6 is an end elevation of a portion 60 of the roller chain,

Figure 7 is a perspective view of the outer link used in the roller chain,

Figure 8 is a perspective view of the inner link used in the roller chain, 65

Figure 9 is a view of the disassembled parts which comprise the sleeve,

Figure 10 is a modified form of the device,

Figure 11 is a section of another modified form of the device, 70

Figure 12 is a section of another modified form of the device, and

Figure 13 is a section of still another modified form of the device. 75

In carrying out my invention, I make use of a standard railway car journal box 1 and of a journal 2 which is rotatably disposed therein. The journal 2 is provided with an annular elongated groove 3, the groove being 80 curved adjacent each end thereof to provide shoulders 4 and 5. Around the journal 2 and disposed in the groove 3 is a roller bearing of the flexible type. The parts heretofore described form no part of the invention 85 except in so far as they cooperate with the parts about to be described.

This roller bearing is clearly shown in Figures 4, 5, 6, 7, and 8. As will be seen in Figures 4 and 5, the bearing comprises two 90 parallel roller chains 6 and 7 which are spaced from each other by rods 8'. Each of the chains 6 and 7 is made up of a plurality of inner and outer links 8 and 9, respectively.

The shape of these links is 95 clearly shown in Figures 7 and 8. The body portion of the outer link 9 is provided with laterally projecting cylindrical portions 10 and 11. These portions extend from the outer side of the link to substantially the middle thereof. The body portion of the outer link 9 is also provided with cylindrical recesses 12 and 13 which are adapted to receive the cylindrical portions 14 and 15 of the inner link 8. It will be seen that the 100 cylindrical portions 10 and 11 have the same diameter as the recesses 12 and 13. Each of the cylindrical portions 10 and 11 is provided with a central bore. The link 8 is 105 provided with pins 16 and 17 which project 110

from the portions 14 and 15 and are adapted to enter the bores 18 and 19 in the cylindrical portions 10 and 11. As clearly shown in Figure 6, the outer surface of the inner link 8 and the outer surface of the outer link 9 lie in the same plane, and are rounded adjacent their upper outer edges for a purpose hereafter described. The rods 8' are adapted to project into bores 20 in the inner links 8. 10 It will be noted that the rods 8' bear against the end walls of the bores 20 and are rigidly secured in place, and therefore prevent the roller chains 6 and 7 from moving inwardly. The links on each rod are prevented from 15 rotation with respect to each other. It will also be observed that every other rod 8' is projected into bores 21 in the outer links 9. These pins have openings therein adjacent the ends thereof, and cotter pins 22 are 20 adapted to be projected through openings 23 in the outer links 9 and into the openings 24 of these pins. In this manner, the roller chains 6 and 7 are prevented from moving inwardly or outwardly and the rods 8' prevent 25 any lateral movement of one chain with respect to the other. The inner links 8 are also provided with bores 25 and 26 which are adapted to receive trunnions 27 of roller bearings 28. The ends of the roller bearings 30 do not abut against the inner surfaces of the chains 6 and 7 and are therefore permitted to play slightly back and forth between the roller chains 6 and 7.

It will be observed that this construction 35 provides a flexible roller bearing. The bearings 28 are permitted a slight movement on their longitudinal axis, but are prevented from any lateral movement with respect to the links 8. The links 8 and 9 are pivotally secured 40 to each other by means of the pins 16 and 17, thus giving the roller bearing the desired flexibility and accurately spacing the roller.

As heretofore stated, I mount the roller bearing in the groove 3 of the journal 2 and mount a sleeve 29 thereover. This sleeve is composed of two or more sections 30 and 31 which are cylindrical in shape and are clearly shown in Figure 9. Each section is 45 provided with a tooth 32 which is adapted to project into a depression 33 of the other section when the two sections are assembled. Each section is also cut longitudinally at 34, thus giving the required resiliency thereto. 50 As will appear in Figure 1, the section 31 is first inserted into the box 1 and is disposed over the roller bearing. The section 30 is also inserted into the box in a like manner and is disposed over the roller bearing. 55 It will be apparent that by inserting the tooth 32 into the depression 33 of the section 31, the two sections will be held together as a unit. The section 30 is also provided with a recess 35 which is adapted to receive a lug 60 36 carried by an oil pan 37. The pan 37 is

clearly shown in Figure 1, and is provided with a depression 38 therein into which the sleeve 29 extends. The sleeve may be composed of a plurality of plane cylinders if so desired. The pan 37 is also yieldingly held 70 in engagement with the lower portion of the sleeve 29 by means of a spring 39. The roller bearing as it revolves with the journal 2 will therefore be automatically oiled, since the lower portion of the roller bearing is 75 immersed in the oil 40 carried by the pan 37. The pan 37 has curved side walls 40, as clearly shown in Figure 3, thereby providing 80 an effective means for returning the oil to the bottom of the pan.

A hood 41 of the shape shown in Figures 1, 2, and 3 is disposed over the top of the sleeve 29 and is securely held in place by a wedge 42. The hood has a semi-cylindrical recess 43 therein which is adapted to receive the roller bearing and is also provided with a substantially flat top 44 on which the lower surface of the wedge 42 abuts. The hood 41 is also provided with a recess 45 into which the upper portion of the sleeve 90 29 projects. It is a well known fact that in railroad engineering the upper surface of the wedge 42 has to be provided with a curve having a radius of 78 inches. As shown in Figure 1, I provide my wedge 42 95 with this curve and also provide the upper surface 44 of the hood 41 with a like curve. The wedge 42 is therefore of uniform thickness, which permits it to be placed in the box 1. The provision of this curve permits 100 the journal 2 to swing slightly in a vertical plane with respect to the box 1. It is obvious that this construction is absolutely necessary in a device of this type, since the journal 2 is swung slightly in a vertical 105 plane when the coach carrying this journal rounds a curve in the track.

From the foregoing description of the various parts of the device, the operation 110 thereof may be readily understood. In assembling my device, I dispose my oil pan in the bottom of the box. I then dispose my roller bearing around the journal 2 and in the groove 3 and lock it in place by means of the cotter pins 22. The pan holds one-half of the bearing in place while the other half is assembled thereto. I then raise the box 1 upwardly with respect to the journal 2 by any means, such as a jack, until the lower portion of the box nearly abuts the journal 2 so that I may then place the two sections 30 and 31 of the sleeve 29 over the bearing in the manner heretofore described. As will be seen in Figure 3, the hood 41 is provided with recesses 46 which permits the hood to be slipped over the bearing and the sleeve 29, and to assume the position shown in Figures 1 and 3. The wedge 42 is then inserted between the top of the box 120 and the hood 41. The jack, which has pre- 125

viously lifted the box, is now removed and thus the full weight of the box is carried by the journal 2. It will be seen that the wedge 42 is provided with two depending 5 lugs 47, which are disposed adjacent the sides thereof, and are adapted to enter recesses 48 in the hood 41 (see Figures 1 and 2). It will also be seen that the lugs 47 are permitted a longitudinal movement in 10 the recesses 48. The hood 41 is also provided with laterally projecting lugs 49 which are adapted to engage lugs 50, the latter being carried by the box 1. The lugs 50 are already provided in the journal boxes 15 of ordinary construction.

It will here be noted that the hood 41 extends down into the annular groove 3 and is spaced therefrom so as to permit slight play between the journal 2 and the hood 41. 20 In like manner, the roller bearing is spaced slightly from the walls of the groove 43 in the hood 41. The wedge 42 is spaced away from the projection 51 carried by the box 1 and therefore permits a slight movement 25 of the wedge with respect to the box. The wedge 42 is also adapted to move with respect to the hood 41. As heretofore stated, the bearings 28 are permitted a slight longitudinal movement between the roller 30 chains 6 and 7. The oil pan is also adapted to move longitudinally with the sleeve. It will therefore be seen that I have provided a device in which play is permitted between the parts thereof and thus the journal 2 is 35 permitted to move longitudinally with respect to the box 1 the required distance of five-eights of an inch. A slight lateral movement is also provided between the journal 2 and the side walls of the box 1 which is clearly shown in Figures 2 and 3. 40 It will here be observed that the hood 41 and the wedge 42 do not abut the lugs 50, but are spaced a slight distance therefrom. The side walls of the pan 37 are also spaced 45 the same distance from the walls of the box. A slight lateral movement of the box 1 with respect to the journal 2 is therefore permitted and the walls of the hood 41, the wedge 42, and the pan 37 abut the lugs 50 and the walls of the box at the same time, thus preventing the hood 41 and the wedge 50 42 from being slightly rotated.

In Figure 10, I show a modified form of the roller bearing used. In this roller bearing, the parts are identical with the parts of the bearing heretofore described except that the bores 25 and 26 are each provided with an annular recess 52 adjacent the outer edge thereof. In the recesses are disposed 55 a plurality of ball bearings 53. This construction provides a more frictionless roller bearing.

It is obvious that from constant use, the journal 2 will be worn and therefore a number of the bearings 28 will not contact with

the journal 2 and the sleeve 29. If the wearing continues, only one of the bearings 28 will support the load at a given time. To obviate this, I provide a sleeve 60 which is substantially elliptical in shape, that is, 70 the two halves thereof have walls concentric with the periphery of the worn journal, these halves having their axes spaced a slight distance from each other. The outer diameter of the sleeve 60 is the same as the outer diameter of the sleeve 29. This construction provides a sleeve which still fits in the recesses 38 and 45 of the pan 37 and the hood 41, respectively. As heretofore stated, the upper portion thereof is concentric with the worn journal and therefore a plurality of bearings 28 will engage the outer surface of the bearing 2 and the inner surface of the sleeve 60. It will be apparent 75 that as the wearing of the journal increases, different sleeves 60, having walls fashioned so as to be concentric with the journal, can be substituted for the previous sleeve. It is common practice to use a journal which is four and one-fourth inches in diameter, 80 when new until it has been worn down to three and seven-eighths inches in diameter. With these sleeves, I can use the journal 2 from the time it is new until it has been worn down to a diameter of three and seven-eighths inches, whereupon a new journal is 85 substituted for the old one.

In Figure 12, I have shown another modified form of the sleeve. This sleeve 70 is semi-cylindrical in shape and has lugs 71 integral therewith which are adapted to project into recesses (not shown) in the hood 41. These lugs 71 prevent the sleeve 70 from rotating with respect to the hood 41. Since all of the load bears against the upper portion of the sleeve, a semi-cylindrical sleeve of the shape shown in Figure 12 would be just as effective as the sleeve 29. Of course in this instance, the oil pan 37 could not be used.

In Figure 13, I show a modified form of hood. This hood 80 is composed of three sections 81, 82, and 83, whereas the hood 41 comprises but a single section. This type of hood is employed where difficulties are experienced in assembling the ordinary hood in the box 1.

It will be apparent that the ends of the hood 41 project downwardly into the groove 3 and thus act as a double thrust, since the outer surfaces of the chains 6 and 7 rotate against the inner faces of the groove 43, and the shoulders 4 and 5 of the groove 3 rotate against the outer faces of the hood 41. The outer edges of the hood 41 are also rounded so as to permit the ready assembly of the hood in the box 1. It will also be noted that the sleeve 29 is composed of two sections, since it would be impossible to insert a full length cylindrical or elliptical 125 130

sleeve into the box 1 and over the end of the journal 2.

As heretofore stated, I provide a flexible bearing for journal boxes which permits the journal to move longitudinally and laterally with respect to the box. I also provide a device which can be readily assembled in the standard journal box without altering the construction of the journal or the box or the necessity of disassembling the journal from the box when placing my device therein. It should be noted that there is approximately one-sixteenth inch play between the rollers and links, and one-sixteenth inch play between the links and the hood, whereby the axle is adapted to move one-eighth inch, after which time, the thrust is taken up by the hood and wedge.

I claim:

20. 1. The combination with a railway car journal and a railway car journal box, of a roller bearing disposed over said journal, a sleeve disposed over said bearing, said sleeve being composed of two interlocking sections, and an oil pan disposed below said bearing said bearing, sleeve, and oil pan being assembled in said box without the necessity of removing said journal from the box, said sleeve engaging with said oil pan to hold the latter in place.

25. 2. The combination with a railway car journal and a railway car journal box, of a roller bearing disposed over said journal, a sleeve disposed over said bearing, said sleeve being composed of two interlocking sections, and an oil pan yieldingly disposed below said bearing, said sleeve engaging with said oil pan to hold the latter in place.

30. 3. The combination with a railway car journal and a railway car journal box, of a bearing disposed over said journal, a sleeve disposed over said bearing, said sleeve being composed of two interlocking sections, a hood adapted to cover the upper portions of said bearing and said sleeve, a wedge disposed between said hood and the top of said box, and an oil pan yieldingly disposed below said bearing, said sleeve engaging with said oil pan to hold the latter in place.

35. 4. A roller bearing comprising roller chains, each chain being composed of inner and outer links, rods connecting said inner and outer links, means for locking said outer links to said rods, and bearings disposed between said chains and rotatably carried thereby the outer surfaces of said links forming a smooth continuous surface, said links inclosing the ends of said bearings, whereby said roller bearing acts as a thrust bearing.

40. 5. A sleeve comprising two cylinders, the peripheral abutting edges of said sections being provided with a tooth and a depression, each section having a longitudinal cut

therein extending from said tooth, the tooth of one section being adapted to enter the depression in the other section, whereby said sections are prevented from rotation with respect to each other and are prevented from expanding.

45. 6. A roller bearing comprising a pair of roller chains having smooth continuous outer surfaces, rods disposed between said chains and adapted to lock said chains against any lateral movement, bearings disposed between said chains and having trunnions rotatably mounted in said chains, and anti-friction means disposed around said trunnions and being carried by said chains.

50. 7. The combination with a railway car journal having an annular groove therein, of an oil pan disposed beneath said journal, a roller bearing mounted in said groove, said roller bearing comprising sections which are adapted to be secured to each other, and said pan being adapted to support one of the sections of said roller bearing and to hold it in engagement with the groove while the other section is being secured thereto.

55. 8. The combination with a railway car journal box and a journal therefor, said journal having an annular groove therein, of a roller bearing consisting of sections adapted to be disposed around said journal and in said groove, and an oil pan disposed beneath said journal and being adapted to hold one of the sections of said roller bearing in engagement with the journal while the other section is secured to the first named section.

60. 9. The combination with a standard railway journal box having a downwardly extending standard lug adjacent to the open end thereof, and a standard railway car journal disposed in said box, of a hood adapted to be carried by said journal, said hood having a curved upper surface, a wedge adapted to be disposed between the hood and the top of said box, said wedge having a curved upper and lower surface, whereby said wedge may readily be passed between the hood and the lug and be inserted into the box, said hood having recesses in the outer end thereof and said wedge having lugs adapted to be received in said recesses, whereby the outward thrust of the journal against the hood may be transmitted to the wedge and through said wedge to the lug of said box.

65. 10. The combination with a railway car journal having an annular groove therein, of a roller bearing disposed in said groove, a sleeve mounted on said roller bearing, and an oil pan disposed beneath said sleeve and having a recess adapted to snugly receive a portion of said sleeve.

70. 11. The combination with a railway car journal having an annular groove therein, of a roller bearing disposed in said groove,

a sleeve mounted on said roller bearing, and an oil pan disposed beneath said sleeve and having a recess adapted to snugly receive a portion of said sleeve, said oil pan projecting in front of the end of said journal.

12. The combination with a railway car journal having an annular groove therein, of a roller bearing disposed in said groove, a sleeve disposed around said roller bearing, and an oil pan yieldingly held in engagement with said sleeve, said sleeve sparing said pan from said journal.

13. The combination with a standard railway car journal box having a downwardly extending standard lug in the front thereof, and a standard railway car journal, of a hood carried by said journal, said hood having a curved upper surface, the ends of said hood being curved more sharply than the central portion thereof, a wedge having curved upper and lower surfaces conforming to the curved upper surface of said hood, said wedge having its ends curved more sharply than the central portion thereof, whereby said wedge may readily be passed between the hood and the lug and be inserted in the box without the necessity of removing the journal from the box.

14. A roller bearing comprising chains

composed of a plurality of inner and outer links, whose outer surfaces form one continuous plane, rollers carried by said chains, said chains inclosing the ends of said rollers whereby said bearing is adapted to take up end thrusts.

15. A roller bearing comprising chains composed of a plurality of inner and outer links, whose outer surfaces form one continuous plane, each link of one chain being rigidly connected to the corresponding link of the opposing chain, whereby said bearing is adapted to take up end thrusts and bearings disposed between said chains and being carried thereby, said chains inclosing the ends of said bearings.

16. A roller bearing comprising endless chains composed of a plurality of inner and outer links, whose outer surfaces form one continuous plane, each link of one chain being rigidly connected to the corresponding link of the opposing chain, rollers carried by said chains, said chains inclosing the ends of said rollers, certain of said outer links being removably secured to each other, whereby the bearing may be separated into two or more portions and readily assembled.

HUBBARD PARKER.
